UNITED STATES PATENT OFFICE.

JOHN PARKER, OF PHILADELPHIA, PENNSYLVANIA, ASSIGNOR OF ONE-HALF TO THOMAS NICHOLS, OF NEWARK, NEW JERSEY.

HAT-BRIM CURLER.

SPECIFICATION forming part of Letters Patent No. 242,686, dated June 7, 1881.

Application filed March 24, 1881. (No model.)

To all whom it may concern:

Be it known that I, JOHN PARKER, a subject of the Queen of Great Britain and Ireland, residing in Philadelphia, Pennsylvania, have 5 invented an Improvement in Hat-Brim Curlers, of which the following is a specification.

The object of my invention is to facilitate the curling of the brims of hats with the usual hand-tool, and this object I attain by providing said tool with a gage adapted to bear upon a guide on the hat-supporting bed, all as hereinafter fully set forth.

In the accompanying drawings, Figure 1 is a view of a brim-curling tool provided with a 15 gage in accordance with my invention, the hat-supporting bed being shown in section; Fig. 2, a plan view, and Fig. 3 a view of a modification.

A is a hat-supporting bed, which is, in the 20 present instance, made with a hollow annular portion adapted to be heated by steam; but the construction of the bed may be modified as desired so long as it affords a proper support for the hat B, the latter being held in place 25 on the bed by any suitable system of clamping devices.

The brim-curling tool shown in the drawings is similar to that in general use at present, and consists of a block, D, with handle E, edge- 30 turning roller a, turn-plate b, and presser- roller d, so that as the tool is traversed in the direction of the arrow the edge of the hat-brim is turned or curled over by the action of the roller a and plate b, and said curled portion is flattened by the pressure of the roller d.

In curling hat-brims with a hand-tool such as that shown and described the extent to which the brim is turned or curled depends upon the course of the tool in respect to the 40 crown or body of the hat, and hitherto this course has been determined by the judgment of the operator; hence the operation of brim-curling as now performed requires the exercise of great care and demands the employment of skilled labor. This I overcome to a 45 great extent by attaching to the tool a gage, J, adapted to act in conjunction with a guide, F, on the hat-supporting bed, the gage being

adjustable in respect to the block D of the tool, so as to vary the position of the latter in 50 respect to the hat crown or body, and thus govern the extent to which the brim is curled. The gage J has at its opposite ends rollers m m, and during the manipulation of the tool these rollers are caused to press firmly against the 55 guide F, the latter being thereby caused to govern the angle assumed by the tool in working around the ends of the hat. The rollers m are arranged at equal distances from the center line of the turn-plate b, so as to prevent 60 twisting of the latter and interference with the proper curling of the brim.

The guide F may form part of the bed A, if desired, instead of being detachable therefrom; or the guide may be constructed to fit over the 65 crown of the hat, as shown in Fig. 3, instead of being applied to the bed; but the latter plan is preferred.

The character of the curling-tool may also be varied, that shown being selected because 70 it is the one now commonly in use.

I claim as my invention—

1. The combination of a hat-brim-curling tool having a handle, E, whereby it is manipulated, with a gage carried by the tool and 75 adapted to bear upon a guide, whereby the course of the tool during the manipulation of the latter is determined, as set forth.

2. The combination of a hat-brim-curling tool having a handle, E, whereby it is manipulated, with a gage adapted to bear upon a guide, said gage being carried by the tool, but being adjustable in respect thereto, as set forth.

3. The combination of the hand brim-curling tool, the guide F, and the gage J, carried by the tool, and having rollers m m at the ends, as set forth.

In testimony whereof I have signed my name to this specification in the presence of two sub- 90 scribing witnesses.

JOHN PARKER.
